Primary Examiner — Jack Reickel*Assistant Examiner* — Bobby W Jones, II(74) *Attorney, Agent, or Firm* — Andrew F. Young, Esq.; Nolte Lackenbach Siegel(57) **CLAIM**

The ornamental design for an air vent module, as shown and described.

DESCRIPTION

FIG. 1 is a front top perspective view of an air vent module showing my new design.

FIG. 2 is a rear bottom perspective view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a front elevation view thereof; and,

FIG. 8 is a rear elevation view thereof.

The dash-dash lines demarcate the boundary of disclaimed portions that form no part of the claimed design. No claim is made to portions that are not shown.

1 Claim, 8 Drawing Sheets(56)
